UNITED STATES PATENT OFFICE.

HENRY DAVIS, OF NASHVILLE, TENNESSEE.

DRILL-OILER.

1,112,198.

Specification of Letters Patent. Patented Sept. 29, 1914.

Application filed September 24, 1913., Serial No. 791,572.

To all whom it may concern:

Be it known that I, HENRY DAVIS, a citizen of the United States, residing at Nashville, in the county of Davidson, State of 5 Tennessee, have invented certain new and useful Improvements in Drill-Oilers; and I do hereby declare the following to be a full, clear, and exact description of the invention, such as will enable others skilled 10 in the art to which it appertains to make and use the same.

This invention relates to improvements in attachments for metal drills, and particularly to an oiling attachment for the 15 drill bits therefor.

The principal object of the invention is to provide a simple oiling device which can be readily attached to the ordinary metal drilling or boring machine to keep the bit 20 well supplied with lubricant.

Another object is to provide a lubricating device which is readily attachable to the ordinary drilling machine frame and which can be thrown out of position when 25 changing bits.

A still further object is to provide an oiling device of this character which will move up and down with the drill bit as the bit progresses through the work.

30 Other objects and advantages will be apparent from the following description, when taken in connection with the accompanying drawings.

In the drawings: Figure 1 is a side elevation of a portion of a drilling machine showing my oiling attachment thereon. Fig. 35 2 is an end elevation. Fig. 3 is an enlarged detail of the hinged joint. Fig. 4 is a detail sectional view of the spout or nozzle 40 of the oil conveying pipe.

Referring particularly to the accompanying drawings, 10 represents the upright post or standard of the drilling machine which carries the frame 11 supporting the usual 45 driving shaft 12, the bit shaft 13 and gearing 14. On the lower end of the bit shaft is a drill chuck 15 which carries the drill bit 16. Secured to the post 10 by means of the clamps 17 is a vertical member 18 to the 50 upper end of which is adjustably secured an outwardly extending bar 19. Connected to the outer end of the bar by means of the hinged joint 20 is a clip 21, this clip being secured by the set screw 21' to the

vertical pipe 22 which connects at its upper 55 end with the oil tank 23. Connected to the lower end of the pipe 22 by means of an elbow 24 is a horizontally extending pipe 25. In the end of this pipe is secured to the casing of a turning plug valve 26 a 60 discharge nozzle 27 extending from the opposite side thereof and in line with the pipe. This nozzle 27 is arranged to engage against the drill bit 16 so as to permit oil to flow therefrom to the bit when the valve 65 is opened. When it is desired to release the nozzle from the bit, as when changing bits, the tank and depending pipe are first slipped up through the clip 21 and then swung outwardly on the hinged joint 20 as 70 will be readily apparent from an inspection of the drawings. Secured to the depending pipe 25 and extending toward the drill chuck is a supporting member 29, the free 75 end of which rests on the upper shoulder of the chuck and supports the device in proper position. This member is firmly attached to the pipe 22, by means of the set screw 29', and supports the oiling device so that the stem of the valve always 80 engages the same part of the drill bit, and moves up and down with the bit, the connection at 21 permits the pipe 22 to slide easily therethrough when the drill is moving up or down.

It will thus be seen that I have provided a simple oiling device which can be readily attached to an ordinary drill frame and which will always be in contact with the 85 drill bit to keep the bit well oiled.

What is claimed is:—

1. An oiling device for a drill comprising a support arranged to be clamped to the frame of the drill, a bar adjustably connected to the support, a guide clip hinged 95 to the bar, an oil tank disposed above the clip, an oil pipe connected to the tank and extending loosely through the clip, a supporting member rigidly and detachably connected to the pipe and arranged to engage 100 with a drill chuck, a valve in the pipe, and a nozzle carried by the pipe and arranged to be disposed against the drill bit.

2. An oiling device for a drilling machine comprising a support mounted on the 105 machine, an oil reservoir, an oil conduit connected to the reservoir and leading to the drill bit, means carried by the conduit

and resting on the drill chuck whereby the reservoir and conduit move with the drill bit, and movable means forming a part of the support and slidably receiving the conduit, whereby said conduit is capable of being moved toward and away from the drill bit.

In testimony whereof, I affix my signature, in the presence of two witnesses.

HENRY DAVIS.
